UNITED STATES PATENT OFFICE.

EDGAR S. BOTT AND ARTHUR S. FUNK, OF LA CROSSE, WISCONSIN, ASSIGNEES TO LA CROSSE RUBBER MILLS CO., OF LA CROSSE, WISCONSIN, A CORPORATION OF WISCONSIN.

DESIGN FOR A RUBBER BOOT.

Application filed May 10, 1926. Serial No. 17,639. Term of patent 14 years.

To all whom it may concern:

Be it known that we, EDGAR S. BOTT and ARTHUR S. FUNK, citizens of the United States, residing at La Crosse, in the county of La Crosse and State of Wisconsin, have invented a new and original Design for Rubber Boots, of which the following is a specification, reference being had to the accompanying drawing, forming part thereof.

Figure 1 is a front perspective view of a rubber boot embodying our design.

Figure 2 is a rear perspective view of the same.

Figure 3 is an enlarged detail showing the ribbed rubber decoration of the boot upper.

We claim:

The ornamental design for a rubber boot, as shown.

ARTHUR S. FUNK.
